Primary Examiner — Richard Edgar*Assistant Examiner* — Alexander J David(74) *Attorney, Agent, or Firm* — Womble Bond Dickinson (US) LLP(57) **CLAIM**

The ornamental design for a reamer head as shown and described.

DESCRIPTION

FIG. 1 is a perspective view of my design of a reamer head; FIG. 2 is a front view of the reamer head of FIG. 1; FIG. 3 is a back view of the reamer head of FIG. 1; FIG. 4 is a left view of the reamer head of FIG. 1; FIG. 5 is a right view of the reamer head of FIG. 1; FIG. 6 is a top view of the reamer head of FIG. 1; FIG. 7 is a bottom view of the reamer head of FIG. 1; FIG. 8 is a cross-sectional view taken along section line 8-8 of FIG. 2; and, FIG. 9 is a cross-sectional view taken along section line 9-9 of FIG. 7.

The dash-dash lines in the figures represent portions of the reamer head that form no part of the claimed design. The dash-dot lines of FIG. 9 illustrate a boundary which forms no part of the claimed design.

1 Claim, 9 Drawing Sheets(56)
